CONTROL VALVE MECHANISM

Pierre Audemar, La Garenne-Colombes, France

Application August 25, 1947, Serial No. 770,525
In France February 27, 1946Section 1, Public Law 690, August 8, 1946
Patent expires February 27, 1966

4 Claims. (Cl. 137—112)

1

This invention relates to control valve mechanism for use in connection with hydraulic transmission systems comprising two transmitters constituted each for example by a piston displaceable in a cylinder, both cylinders being interconnected by a pipe line into which is branched, at right angles thereto, a conduit adapted to operate the receiver such for example as the piston of a hydraulic jack.

The problem is how to act upon one of said transmitters without sending the fluid medium into the other, while introducing the same into the receiver.

With a view to solving this problem it has been proposed to mount in the pipe line interconnecting the two transmitters, and on both sides of the conduit leading into the receiver, two valve seats between which may move freely a double-acting valve adapted, when pushed by the fluid medium coming through the pipe line from one transmitter that has just been actuated, to cut off the communication with the other.

Such an arrangement, however, while behaving pretty well when sudden transmissions are necessary determining a quick displacement of the hydraulic fluid, is inefficient when slow displacements are dealt with, because the double-acting valve remains in its median position and allows the hydraulic fluid to flow into the un-actuated transmitter, a fact which presents a serious inconvenience.

The present invention has for its object to provide in a simple and efficient structure a novel control valve mechanism which shall obviate said inconvenience and permit the receiver to be operated by one or the other of the two transmitters, without allowing the hydraulic fluid to penetrate into the unactuated transmitter, whatever may be the velocity with which the piston of the actuated transmitter is displaced.

With this and other objects in view, the invention resides in the novel features of construction and arrangements of parts, as more fully hereinafter set forth.

In the accompanying drawing, in which like reference characters indicate like parts,

Fig. 1 is a diagrammatic view showing a hydraulic transmission system comprising two transmitters, a receiver and a control valve mechanism according to the present invention;

Fig. 2 is a diagrammatic view showing a hydraulic transmission system comprising four transmitter, a receiver and three control valve mechanism according to the invention;

2

Fig. 3 is a longitudinal sectional view showing the structure of the control valve mechanism according to the invention; and

Fig. 4 shows a portion of the device of Fig. 3 wherein the parts occupy another position.

Referring first to Fig. 1, designated by 1 and 2 are two transmitter units, 3 is a receiver unit, 6 is a control valve mechanism designed according to the present invention, 4 is a conduit leading from the control valve mechanism 6 into the receiver unit 3, while 5a and 5b are pipes connecting the transmitter units 1 and 2, respectively, with the control valve mechanism 6. The piston of the receiver unit 3 is constantly acted upon by a spring so that the piston may be restored to its initial position whenever the transmitters become inoperative.

In Fig. 2 is shown a hydraulic transmission system comprising four transmitter units. In this case it is necessary to provide three control valve mechanism according to the invention. The receiver may be constituted for example by a differential hydraulic jack of which the face opposed to that acted upon by the liquid pressure exerted by one of the transmitters is constantly under a hydraulic pressure exerted through a conduit C.

Figs. 3 and 4 are enlarged showings of the control valve mechanism 6. In these figures, 7a is the valve seat corresponding to the pipe 5a, while 7b is a valve seat corresponding to the pipe 5b. Arranged between these two seats is a two-face valve 8 carrying two coaxial rods 9a and 9b, respectively. Designated by 10a and 10b are two pistons arranged on both sides of the conduit 4. Within each piston is provided a chamber in which is positioned a ball 12 adapted to close a coaxial opening 13 and to be pressed against the latter by a spring 11. Designated by 15 is an abutment adapted to limit the displacements of the ball 12 within the chamber, while by 16 are designated openings permitting the chamber to communicate with the pipes 5a and 5b, respectively. The two pistons 10a and 10b are urged, the former toward the left and the latter toward the right as viewed in Fig. 3, by springs 17.

The operation is briefly as follows: If for example the transmitter unit 2 is actuated, the hydraulic fluid will flow into the valve mechanism 6 through pipe 5b and push to the left the piston 10b whose ball 12, when contacting the valve rod 9b, will move the two-face valve 8 to the left and finally apply said valve against its seat 7a. From this time on, as the piston

10b acted upon by the liquid pressure keeps on moving to the left, the movement of ball 12 is stopped by the rod 9b so that the right end of the opening 13 will move away from the ball 12 to permit communication between the chamber within the piston 10b and the conduit 4. Subsequent movement of the piston 10b will bring ball 12 in contact with the abutment 15, whereafter the piston 10b is immobilized in a position indicated by dash-and-dot lines 10c in Fig. 4, the liquid under pressure being thus allowed to flow freely through the piston chamber, past the ball 12, and further through the intermediate conduit 4 into the receiver unit 3. It is clear that the displacement of the valve 8 is entirely independent from the velocity of flow of the hydraulic fluid. It follows therefrom that owing to the device of the invention a faultless hydraulic transmission can be secured in all conditions of operation.

The device of the invention lends itself to many applications. Thus, for example, it may be used for controlling brakes, for example brakes of a railway train. It may further be applied to all sorts of transmissions to a distance.

This device, however, is particularly intended to be applied to double transmissions, more particularly to double transmissions for use in connection with flying machines to which it assures full working safety.

It will be understood that the invention is not limited to the particular examples shown, as changes may be made therein without substantially departing from the spirit of the invention which is intended to be defined in the accompanying claims.

What is claimed is:

1. A control valve mechanism for use in connection with hydraulic transmission systems including at least two transmitters and one receiver, comprising a casing having two inlet chambers and an outlet chamber located between said inlet chambers and communicating with the same through ports, a two-face valve member located between said ports for controlling communication between each of said inlet chambers and said outlet chamber, a stem extending from each face of said valve member, a pressure responsive valve operating element in each inlet chamber having an opening in alignment with said stems for establishing a communication between the inlet ports and the outlet chamber, and valve means for controlling said openings adapted to act on said stems so as to engage said two-face valve member to interrupt communication between one of said inlet chambers and said outlet chamber on initial movement of the valve operating element in the other inlet chamber, and to permit communication between the inlet port of said other inlet chamber and said outlet chamber on subsequent movement of said element.

2. A control valve mechanism for use in connection with hydraulic transmission systems including at least two transmitters and a single receiver, comprising two parallel cylindrical inlet chambers provided with inlet ports, an outlet chamber between said inlet chambers and communicating therewith through ports, a two-face valve member in said outlet chamber located between said ports for controlling communication between said inlet chambers and said outlet chamber, a stem extending from each face of said valve member into one of said inlet chambers, a hollow piston in each of said inlet cham-

bers responsive to the liquid pressure introduced into said inlet chambers through one or the other of said inlet ports, each piston having an axial opening in alignment with said stems for establishing communication between the spaces at the front and rear of the piston, and check valves for controlling said openings adapted to act on said stems so as to engage said two-face valve member to interrupt communication between one of said inlet chambers and said outlet chamber on initial movement of the piston in the other inlet chamber, the arrangement being such that the check valve in said other inlet chamber is opened by the corresponding stem to permit communication between the inlet port of said other inlet chamber and the outlet chamber on subsequent movement of the piston in said other inlet chamber.

3. A control valve mechanism for use in connection with hydraulic transmission systems including at least two transmitters and one receiver connected by pipe lines, comprising a casing, two spaced valve seats arranged within said casing and corresponding each to the respective inlet pipe supplying the liquid under pressure, a two-faced valve member located between said valve seats and adapted to apply against either of them, two opposed rods protruding each from the corresponding valve face, two hollow pistons arranged each within the corresponding end portion of said casing between said rods and said inlet pipes, resilient means interposed between each valve seat and the corresponding piston for limiting the displacement of the latter, a valve arranged in a hole in each piston and adapted, when the piston is acted upon by the incoming liquid, to cause the two-faced valve member through its respective rod to apply against one of its seats, and intermediate piping leading from the space between said valve seats into said receiver.

4. A control valve mechanism for use in connection with hydraulic transmission systems including at least two transmitters and one receiver connected by pipe lines, comprising a casing, two spaced valve seats arranged within said casing and corresponding each to the respective inlet pipe supplying the liquid under pressure, a two-faced valve member located between said valve seats and adapted to apply against either of them, two opposed rods protruding each from the corresponding valve face, two pistons arranged each within the corresponding end portion of said casing between said rods and said inlet pipes, a counterspring interposed between each valve seat and the corresponding piston for limiting the displacement of each piston, a chamber arranged within each piston, adapted to be filled up with the incoming pressure liquid and provided on its front face with an opening co-axial with one of said valve rods, a ball disposed in front of said opening and displaceable within said chamber, a second counterspring and an abutment interposed between the bottom of said chamber and said ball for limiting the displacement of the same, and an outlet pipe leading from the space between said valve seats into said receiver, said ball being intended to close said opening when its piston is unactuated by the pressure liquid, but when it is actuated thereby, first to cause the said two-faced valve member by acting upon its respective rod, to close its remote seat and then to be moved away from said opening by said rod so as to allow said pressure liquid to flow freely through said

chamber, past said ball, through said outlet pipe out of said casing and into said receiver.
